UNITED STATES PATENT OFFICE.

AUSTIN C. EVANS, OF SPRINGFIELD, OHIO.

HARROW.

SPECIFICATION forming part of Letters Patent No. 319,894, dated June 9, 1885.

Application filed February 9, 1885. (No model.)

To all whom it may concern:

Be it known that I, AUSTIN C. EVANS, a citizen of the United States, residing at Springfield, in the county of Clark and State of Ohio, 5 have invented certain new and useful Improvements in Harrows; and I do declare the following to be a full, clear, and exact description of the invention, such as will enable others skilled in the art to which it appertains to make and to use the same, reference being had to the accompanying drawings, and to the letters and figures of reference marked thereon, which form a part of this specification.

My invention relates to improvements in 15 harrows.

My invention relates to that class of harrows which are in sections hinged together, the outside sections being operated by a longitudinal lever extending centrally over the middle section and connected by chains with the former, said lever being free to move toward either side of the rear end in elevating the sections.

This invention is designed as an improvement upon my former patents, dated November 1, 1881, No. 248,850, and July 24, 1883, 25 No. 281,755, on the same implement, and is intended to simplify the parts connecting the rear of the lever with the strap or bar on the rear of the middle section.

Figure 1 is a plan view of a three-section harrow with my improvement applied thereto. Fig. 2 is a rear elevation of the same with a cross-section of the lever at the point of connection with the rear end of the middle section. Fig. 3 is a side elevation of the middle section with the lever, the chains connecting the latter with the outside sections being removed.

A is the middle section of the harrow, which 40 is constructed in the same manner as shown in Patent No. 236,793, issued to me January 18, 1881; in its general form being made of wooden beams connected across the ends by a bar of iron to which the outside sections, B and B, are 45 hinged.

Over the central longitudinal line of section A is a long lever, C, its front end being loose in a guideway on the front bar of the section. The rear end of lever C extends back beyond 50 the harrow a sufficient distance to allow of its

being easily manipulated by the operator who walks behind the harrow.

Immediately over bar a, on the rear of section A, is a long bow-shaped bar, b, the ends of which are bolted to bar a by bolts b' b', 55 which extend through the latter and through the rear ends of the outer beams of the section A, thus firmly securing bar b to the latter. Bar b extends from one side of section A to the other, so that the harrow may be operated 60 on the most uneven ground without having the lever pulled off from its elevated portion by either of the side chains, a', connecting it with the outside sections. The horizontal portion of bar b is sufficiently elevated for the lever (when lying thereon) to be within easy reach of the operator, and extends in a plane parallel with that of the harrow-section A. A short piece of chain, c, with a ring, c', on the end encircling bar b connects the lever C with the 70 latter. When lever C is thrown to one side to elevate one of the outside sections B, ring c' slides on bar b to the opposite side, as seen in the dotted lines, Fig. 2. When the operator releases the lever, it is again drawn 75 back to its normal position. The free play of the lever from one side to the other of section A on bar b allows either one of the harrow-sections to drop below the plane of the middle section, allowing the implement to better 80 conform to the surface of rough and uneven ground than if the lever were confined to a fixed point at the rear end of the harrow, as is the case in my former patents before mentioned, in one of which the lever rests in a 85 fork and in the other it is held by a hook at the center of the rest-bar. The lever being connected with the bar b is at all times in readiness to elevate the rear of the harrow.

I claim as my invention—

1. In a three-section harrow having its sections flexibly connected together, a lever with its front end loosely pivoted extending over the middle section, chains connecting said lever with the outside sections, an elevated bar 95 on the rear of said middle section extending from side to side of the same, and a short chain connecting said lever and bar provided with a ring on its lower end encircling the latter and adapted to slide thereon, whereby said 100

lever is free to move in a horizontal plane over said middle section in elevating the outside sections without disconnecting it from said elevated bar, as set forth.

5 2. In a three-section harrow having its sections flexibly connected and operated by a lever pivoted over the middle section and connected by chains with the outside sections, the combination, with the middle section and said 10 lever, of an elevated bar on the rear end of said middle section and parallel therewith, its ends bent downwardly and attached to the latter, and a chain connecting said bar and lever together, whereby said lever may be freely 15 operated from side to side of said middle sec-

tion in the line of said bar without disconnecting it from the latter, as set forth.

3. In combination with the pivoted hand-lever and the bar on the rear of the middle section, the chain or other like means for connecting the former with the latter adapted to slide loosely on said bar in operating said lever, as set forth.

In testimony whereof I affix my signature in presence of two witnesses.

AUSTIN C. EVANS.
